CLAIM

(51) LOC (10) Cl. **12-15**

The ornamental design for a motorcycle tire, as shown and described.

(52) U.S. Cl.

DESCRIPTION

USPC **D12/605**; D12/536

FIG. 1 is a perspective view of a motorcycle tire showing my design;

(58) **Field of Classification Search**

FIG. 2 is a front view thereof;

USPC D12/506, 530, 533-567, 570, 605

FIG. 3 is a top view thereof;

CPC B60C 1/0016; B60C 11/0306; B60C

FIG. 4 is a right side view thereof;

11/0302; B60C 11/11; B60C 11/03

FIG. 5 is a fragmentary enlarged front view showing the details of the tread portion thereof;

See application file for complete search history.

FIG. 6 is a fragmentary enlarged perspective view showing the details of the tread portion thereof;

(56) **References Cited**

FIG. 7 is a section view taken along line 7-7 in FIG. 5;

U.S. PATENT DOCUMENTS

FIG. 8 is a section view taken along line 8-8 in FIG. 5;

D521,925 S * 5/2006 Matsumura D12/536

FIG. 9 is a reference view showing the front view of the portion of the subject design; and,

D521,926 S * 5/2006 Matsumura D12/536

FIG. 10 is a reference view showing the right side view of the portion of the subject design.

D577,656 S * 9/2008 Sueishi D12/536

The broken lines are used to show portions of the tire that are not being claimed, and thus form no part of the claimed design.

D579,406 S * 10/2008 Sueishi D12/536
